UNITED STATES PATENT OFFICE.

EDWARD HANAK, OF HOUSTON, TEXAS.

ELEVATOR.

Application filed April 16, 1926. Serial No. 102,374.

This invention relates to new and useful improvements in an elevator.

One object of the invention is to provide a portable elevator specially designed for the purpose of elevating and stacking heavy articles, such as bales of cotton, packages or articles of any character.

Another object of the invention is to provide a novel type of framework embodying an elevator framework including an elevator frame and an adjustable apron frame thereon and means for elevating and lowering the apron frame; and comprehends, also, a novel type of elevating apron employed and a novel type of stacking apron, associated therewith.

A further feature of the invention resides in the provision of a power unit adjustably mounted on the elevator frame, for the purposes hereinafter specified.

A still further feature of the invention resides in the provision of means for anchoring the elevator in position on the supporting floor to hold the same steady while in operation.

With the above and other objects in view this invention has particular relation to certain novel features of construction, operation and arrangement of parts, an example of which is given in this specification and illustrated in the accompanying drawings, wherein:

Figure 1 shows a side elevation of the elevator, partly in section.

Figure 2 shows a cross sectional view thereof, taken on the line 2-2 of Figure 1.

Figure 3 shows a cross sectional view thereof taken on the line 3-3 of Figure 1.

Figure 4 shows a plan view of the elevator frame, showing a sectional view of the apron frame pivoted thereto.

Figure 5 shows a rear elevation of the elevator, partly in section.

Figure 6 shows a plan view of the stacking apron employed, and

Figure 7 shows an enlarged fragmentary side view of the delivery end of the elevating apron frame.

Referring now more particularly to the drawings, wherein like numerals of reference designate similar parts in each of the figures, the numerals 1, 1 designate the side members of the elevator frame, which are

connected at one end by means of the channel iron 2. At their other ends these side members have bearings 3, 3, in which the transverse shaft 4 is mounted.

There is an elevating apron frame formed with the side members 5, 5, of channel irons whose lower ends having bearings on the shaft 4 adjacent the inner ends of the respective bearings 3. The upper ends of the side members 5 are supported by the adjustable supporting links, designated generally by the numerals 6, 6.

Each supporting link comprises an upper and a lower channel iron designated by the numerals 7 and 8 the former of which are pivoted to the respective side members 5 and the latter of which are pivoted to the respective side members 1, by means of the cross rods 7' and 8' respectively which extend through the side members 5, 5, and 1, 1 respectively and through the adjacent ends of the corresponding channel irons 7 and 8.

The channels 7 and 8 face each other, with their ends overlapping and their respective side flanges abutting. The free ends of the channel irons 7 and 8 have the blocks 9 bolted thereto, each adapted to run in the channel of the opposite iron to hold said irons in alignment. There is a rack 10 bolted to the back side of each channel 7, said racks being in mesh with the respective spur gears 11 which are fixed on the transverse shaft 12, mounted in turn in aligned bearings carried by the channel irons 8. One end of the shaft 12 has a screw gear 13 fixed thereon which is in mesh with the worm 14 which is fixed on the crank shaft 15. By turning the crank shaft the elevating apron frame may be lifted or lowered.

The elevator framework, above described is mounted on the carrier wheels 16, 16, and underneath the front ends of the side members 1 are the castors 17, 17. When in use the elevator is supported on said wheels and castors 16 and 17 and to anchor it against movement, outwardly threaded anchor rods 18, 18, are threaded through the flanges of 100 the brace 2 and their lower ends are pointed to engage said floor.

The upper ends of these rods have the removable cranks 19, by means of which they may be manipulated. When it is desired to move the elevator the rods 18 may

be turned to withdraw them from the floor and the entire elevator then moved about, or turned, on the wheels 16.

Bolted to the upper ends of the side members 5 are the brackets 20, 20, which have transversely aligned adjustable bearings 21, 21, in which the transverse shaft 22 is mounted to rotate. This shaft 22 carries spaced sprocket wheels 23, 23, which are fixed thereon and are in alignment with the sprocket wheels 24, 24, which are fixed on the shaft 4 and operating over these aligned sprocket wheels are the chains 25, 25, which have the transverse spaced slats 26 whose ends ride upwardly as indicated by the arrow in Figure 1, on the upper edges or faces, of the side members 5, and thus form the elevating apron. The under side of this apron is enclosed and protected by the hood 27, which is swung from the side members 5, by the brackets 26.

Slidably mounted on the side members 1, 1, there is a motor frame comprising the angle shaped side bars 29, 29, which are connected by the U-shaped supporting brackets 30, 30, on which the motor 31 is mounted. The motor shaft carries a fixed pinion 32 which is in mesh with a spur gear wheel 33 which is fixed on a transverse shaft 34. This shaft is mounted to rotate in bearings 35, 35, carried by the side bars 29 and has a spur gear 36 fixed thereon which is in mesh with the gear 37 fixed on the shaft 38 which rotates in bearings 39, 39, also carried by the side bars 29. The shaft 38 has a fixed sprocket wheel 40 aligned with a corresponding sprocket wheel 41 fixed on the shaft 4 and a chain 42 operates over these sprockets and transmits rotation from the former to the latter.

The motor 31 and the transmission gearing associated therewith and mounted on the motor frame are movable, as an independent unit, on the elevator frame. Fas-
45 tened on the side members 1, 1, adjacent their forward ends are the tapped bosses 43, 43, with the jack screws 44, 44, threaded through them and abutting the respective bars 29, 29. Through these screws the motor frame may be adjusted to regulate the tension on the chain 42. The tension on the elevator chains 25 may be likewise adjusted through the take up screws, as 45, which are threaded through the webs, as 46, and 50 abut the respective bearings 21.

The numeral 47 designates a delivery, or stacking apron, or platform. This apron is substantially rectangular and it is supported on the spaced arms 48, 48, whose free ends are formed with bearings 49, 49, adapted to receive the shaft 22. Between the arms 48 there is a delivery roller 50 mounted on a shaft 51 which is rotatable in suitable aligned bearings in the arms 48. One 65 end of the shaft 51 has a sprocket 52 which

is aligned with the sprocket 53 fixed on the shaft 22 and a chain 54 operates over these sprockets and transmits rotation from the latter to the former.

This apparatus is particularly adapted 70 for loading railway cars with heavy articles such as bales of cotton, and for similar purposes. In beginning the work the delivery end of the elevating apron frame may be lowered and as work progressed said de-
75 liver end is elevated in order to deliver the articles to be loaded, tier upon tier, the apron 47 being supported upon the last completed tier while making delivery for the next tier to be stacked.

The bales, or boxes, and the like are loaded onto the elevating apron at its lower end and are carried by it up onto the roll 50 and thence by it over the delivery apron, 47.

In some cases it may be found desirable 85 to provide upstanding transverse lugs on the elevating apron. For this purpose there are at certain intervals the bearing members 55, 55, fastened to the ends of the slats 26, and rods as 56 have end bearings in these members and attached to these rods adja-
90 cent said bearings, are the spaced lugs 57, 57. On the upward movement of the apron these lugs will stand in vertical position to hold the load on said apron but as they pass 95 around the upper end of the apron frame their lower ends will contact with the cams 58, 58, carried by the upper ends of the side members 5 and their outer ends will be thrown inwardly and held in such position 100 until they pass within the hood 27.

What I claim is:

1. A device of the character described including an elevating apron frame, side brackets depending therefrom, an elevating apron mounted in said frame, said apron comprising side sprocket chains and spaced cross slats secured thereto and an enclosing hood underneath said frame and supported by said brackets and enclosing said apron underneath, bearing members fastened to the ends of said slats, rods having bearings in said bearing members, lugs fastened to said rods and upstanding from the apron, cams carried by one end of said apron frame and adapted to engage the adjacent ends of said lugs to carry the opposite ends of the lugs inwardly toward the apron to permit said lugs to pass within said hood as the apron revolves.

2. An elevator including an elevator frame, an apron frame pivoted at one end to the elevator frame, adjustable supporting means for the other end of said apron frame, side brackets depending from the apron frame, an endless apron mounted in the apron frame, said apron comprising side sprocket chains and spaced cross slats secured to said chain, means for driving said chains, an enclosing hood underneath the

apron frame and supported by said brackets and enclosing said apron underneath, bearing members fastened to the ends of said slats, rods having bearings in said bearing members, lugs fastened to said rods and upstanding from the apron, cams carried by one end of said apron frame and adapted to

engage the adjacent end of said lug to carry the opposite ends of the lugs inwardly toward the apron to permit said lugs to pass 10 within said hood as the apron revolves.

In testimony whereof I have signed my name.

EDWARD HANAK.
